UNITED STATES PATENT OFFICE.

THOMAS F. TOMLINSON, OF NORFOLK, VIRGINIA.

SIDE FRAME FOR CAR-TRUCKS.

1,196,179.

Specification of Letters Patent. Patented Aug. 29, 1916.

Application filed May 19, 1915. Serial No. 29,181.

To all whom it may concern:

Be it known that I, THOMAS F. TOMLINSON, a citizen of the United States, residing at Norfolk, in the county of Norfolk and 5 State of Virginia, have invented certain new and useful Improvements in Side Frames for Car-Trucks, of which the following is a specification.

This invention relates to truck frames, and 10 has especial reference to the side frames therefor.

An object of this invention is to provide side frames which are detachably associated with the truck, to permit expeditious removal of the frames, although positively retaining the axis from displacement during movement.

A further object of the invention is to provide side frames which will permit removal 20 of the journal boxes, but will positively prevent accidental displacement of the journal boxes, should the hinged ends of the frames become accidentally disengaged, at the same time, requiring a minimum elevation in order to remove the journal boxes 25 from the car frame.

Other objects as well as the nature, characteristic features and scope of my invention will be more readily understood from 30 the following description taken in connection with the accompanying drawings and pointed out in the claim forming a part of this specification.

Referring to the drawings: Figure 1 is a 35 side elevational view of a side frame constructed in accordance with my invention one of the hinged ends thereof being swung downwardly in an open position. Fig. 2 is a detail elevational fragmentary view of a 40 side frame constructed in accordance with my invention, illustrating the application of the same with a car wheel, axle and journal box, said axle and journal box being shown in section, Fig. 3 is a detail enlarged perspective fragmentary view of one of the 45 side frames used in this invention, Fig. 4 is a transverse sectional view of a side frame constructed in accordance with my invention, illustrating the application of the same, 50 and Fig. 5 is a plan view of the bolts used in this invention.

In the drawings, in order to illustrate the application of this invention, car wheels 1 are provided which are rotatably mounted 55 upon axles 2 in the usual manner, the free ends of the axles 2 having journal boxes 3

associated therewith. Flanges 4 are formed upon said journal boxes 3, and are arranged in spaced-apart relation to provide an annular groove 5 in each of said journal boxes, 60 as shown to advantage in Fig. 4.

My improved side frame is generally designated in the drawings at 6 and comprises a skeleton body having a supporting column 7 formed approximately midway its 65 ends and in which a longitudinally extending recess is formed to receive the truck bolster 8 and a spring plank 9 of the usual configuration, the latter being held in spaced-apart relation through the medium of coil 70 springs 10. The terminals of the frame 6 are provided with hinged portions 11, each of said portions comprising an angle iron, one end of which is bifurcated as indicated at 12 for pivotal engagement with the lower 75 end of the body of the frame 6, the opposite end of said right-angled portion being reduced as indicated at 13 and mounted between the branches of a bifurcated portion 14 of the body of the frame 6. When the 80 angled portion 11 on each end of the body of the frame 6 is in a locked position, an oblong opening 15 is provided, adapted for the reception of a journal box, the frame 6 being held from displacement on the journal boxes 85 in either direction, in view of the flanges 4, heretofore described. The angled portions 11 are held in engagement with the frame 6 by bolts 16, the latter being held from displacement by cotter pins 17 although it is 90

to be understood that any of the bolts may be removed, if so desired, and when one bolt is removed on either end, the other bolt will provide an axis, so as to permit the angled portion 11 to be swung either upwardly or 95 downwardly in a vertical plane, thereby permitting the journal boxes to be removed when so desired. It is customary, however, to permit the angled portions 11 to swing downwardly, since the weight of these portions will cause them to gravitate to the farthest point of movement, thereby permitting the journal boxes to be removed when the frame 6 is very slightly elevated, it being, of course, necessary to elevate the frame in 100 view of the bifurcated ends 14 of said frame, said bifurcated portions being turned at right angles to the longitudinal axis of said frame, and serving in the capacity of abutments, so as to prevent the journal boxes 105 from being casually displaced, should the angled portions 11 of said frames be acci-

dentially disengaged by vibration of the rolling stock, etc.

Ears 18 are integrally formed upon the supporting column 7, adapted to support 5 the inside hung brake-shoes in the usual manner.

Although the angled portions 11 are permitted to swing downwardly when it is desired to remove the journal boxes 3, nevertheless movement is limited, in view of the fact that said portions swing in the path of the side frame to abut the latter, since the lower marginal edges 11' of the angled portions, adjacent their pivot points, will engage the shoulders 11² of the side frames as shown to advantage in Fig. 1. The shoulders 11² are formed by reducing the ends of the side frames, as indicated in Fig. 3, said reduced portions being pivotally arranged between the branches of the bifurcations 12. By this construction it will be impossible for the angled portions 11 to swing into contact with the rail ties in the event of casual disengagement of the upper 25 ends of the angled portions, since the latter will not be permitted movement below a plane on a parity with the top of the rails.

It will be understood that the above description and accompanying drawings comprehend only the general and preferred embodiment of my invention and that various minor changes in details of construction, proportion and arrangement of parts may be

made within the scope of the appended claim without sacrificing any of the advantages of my invention. 35

Having thus fully described my invention, what I claim as new and desire to secure by Letters Patent is:

A side frame for car trucks including a body having openings adjacent its terminals to accommodate journal boxes therein, a portion of each terminal being removed to permit engagement of the journal boxes in said openings and removal of the same therefrom, the terminals of said portions being formed to engage corresponding parts of the body, each removable portion being operable on either of its ends as an axis, portions of said body lying in the path of movement of said movable portions to limit their downward movement to a plane on a parity with the base of the truck wheels, the parts of said frame which engage the upper terminals of said removable portions being depended to provide abutments for preventing casual displacement of the side frames in the event of displacement of said movable terminals. 50 55

In testimony whereof I affix my signature 60 in presence of two witnesses.

THOMAS F. TOMLINSON.
